UNITED STATES PATENT OFFICE.

HENRY J. COOK, OF MILWAUKEE, WISCONSIN, ASSIGNOR OF ONE-HALF TO EUGENE M. SHAW, OF MILWAUKEE, WISCONSIN.

HEEL FOR SHOES.

Application filed October 17, 1921. Serial No. 503,226.

To all whom it may concern:

Be it known that I, HENRY J. COOK, a citizen of the United States, and resident of Milwaukee, in the county of Milwaukee, and State of Wisconsin, have invented new and useful Improvements in Heels for Shoes, of which the following is a description, reference being had to the accompanying drawings, which are a part of this specification.

This invention relates to improvements in heels for shoes, and the primary object thereof is to provide novel means for securing the heel to the heel portion of the shoe which is of such construction that the heel may be readily removed from the shoe should it become worn and another heel substituted.

In its preferred form the invention contemplates a plate secured to the under side of the heel portion of the shoe and a plate secured to the upper side of the heel; and a more specific object of the invention is to provide co-operating members on said plates which are preferably perforated and so arranged that a locking pin may be inserted through said members and the heel readily and effectively secured to or removed from the heel portion of the shoe.

A further object of the invention is to provide means, in combination with the co-operating members formed on the plates, to prevent lateral displacement of the heel relative to the heel portion of the shoe which means is preferably in the form of a depending flange formed integrally with the plate secured to the heel portion of the shoe and which preferably extends around both sides and the rear of the heel.

The invention consists in the novel constructions, arrangements and devices to be hereinafter described and claimed for carrying out the above stated objects and such other objects as will appear from the following description of a certain preferred embodiment illustrated in the accompanying drawings, wherein—

Fig. 1 is a side elevational view of the heel portion of a shoe and a heel applied thereto embodying the principles of the invention, a portion of the heel and the heel portion of the shoe being shown in section;

Fig. 2 is a front elevational view of the heel portion of the shoe and the heel applied thereto as shown in Fig. 1;

Fig. 3 is a plan view of the heel ready to be applied to the shoe;

Fig. 4 is an inverted plan view of the heel portion of the shoe; and

Fig. 5 is a perspective view of the locking means preferably employed for securing the heel to the heel portion of the shoe.

Like characters of reference designate like parts in the several views.

Referring now to the drawings, it will be seen that the heel portion 7 of the shoe has secured to its under side a plate 8 by means of a plurality of fastening members 9. The heel 10 has a plate 11 secured to its upper side by fastening members 12. The plates 8 and 11 are provided with co-operating members which in combination with suitable locking means are adapted to secure the heel to the heel portion of the shoe. In the preferred form of the invention the plate 8 is stamped so as to provide a plurality of depending members or lugs 13 which extend into registering recesses 14 formed in the plate 11. The portions 15 of the plate 11 between the recesses 14 are struck upwardly and project into suitable depressions 16 provided in the plate 18 between the members 13. In other words, the struck-down portions 13 of the plate 8 constitute perforated lugs which are brought into register with the upwardly struck perforated lugs 15 of the plate 11 when the heel is properly positioned with respect to the heel portion of the shoe.

The respective co-operating members of the two plates are preferably arranged in two rows substantially as shown in Figs. 2, 3 and 4 of the drawings, which rows are substantially parallel to the sides of the heel so that the prongs of a U-shaped locking pin 17 may be readily inserted through the respective aligned perforations of the co-operating members of the plates. The locking pin is formed with an outwardly curved portion 17^a to facilitate inserting and withdrawing it from the members 13 and 15. If desired, the plate 11 may be cut away at 11^a to more readily insert a tool to withdraw the locking pin.

To prevent lateral displacement of the heel relative to the heel portion of the shoe, the plate 8 is preferably formed with a depending flange 18 which, as clearly shown in Fig. 4, preferably extends around both sides and the rear portion of the heel. The heel 10 is

formed with a peripheral groove 19 which is adapted to receive the flange 18 when the heel is brought into proper engagement with the heel portion of the shoe. The flange 18 5 relieves the co-operating members 13 and 15 of the two plates from considerable strain and the plates 8 and 11 need not be made of as heavy material as they would have to be if the flange were not provided. The 10 flange also covers the joint between the heel portion of the shoe and gives the heel a more finished appearance.

From the foregoing description it will be readily apparent to those skilled in the art 15 that a heel constructed according to the principles of the invention may be readily applied to or removed from a shoe. The plates 11 may be fastened to the heels at the factory and sold in sets in combination with 20 the plates 8. The heel may be readily applied to any shoe by any person not particularly skilled in the use of tools or in the art of shoemaking, it being merely necessary to level off the old heel to the proper height 25 and secure the plate 8 thereto. Once the

plate 8 is secured to the shoe the heel may be quickly secured in place as heretofore described.

I claim:

The combination of a plate adapted to be 30 affixed to the heel of a shoe, said plate having depending loop members arranged in two rows and also having a depending flange extending around the sides and rear thereof, a heel arranged to fit said shoe heel, a 35 plate affixed to said heel and having depressed portions and raised loop portions arranged in two rows and cooperating with the first mentioned plate depending loop members, said last mentioned plate being 40 further provided with a groove extending around the sides and rear thereof to receive said depending flange and secure said heel against lateral movement, and a U-shaped locking pin adapted to be inserted through 45 said cooperating loop portions to removably secure the heel to the heel of the shoe.

In testimony whereof, I affix my signature.

HENRY J. COOK.
